REFRIGERATOR

Giles C. Mitchell, Kansas City, Mo.

Application May 20, 1940, Serial No. 336,215

11 Claims. (Cl. 62—89)

This invention relates to refrigerators and more particularly to refrigerators designed for domestic use, the principal objects of the invention being to provide a convenient relatively economical and highly efficient refrigerator of such a character.

Other objects of the invention are to so arrange the refrigerator as to conserve space in a kitchen or other room of a home; to provide a plurality of cooling compartments and for cooling the same to different temperatures depending upon the character of articles to be refrigerated; to provide for sealing certain of the compartments relative to outside air when another compartment is exposed; to facilitate exposure of a compartment as and when desired; to facilitate the handling and storage of relatively large articles to be refrigerated; and to provide improved elements and arrangements thereof in a refrigerator of the character and for the purpose noted.

In accomplishing these and other objects of the present invention, I have provided improved details of structure, the preferred forms of which are illustrated in the accompanying drawings, wherein:

Fig. 1 is a perspective view of a refrigerator embodying the present invention, part of the top thereof being cut away to more clearly illustrate its construction.

Fig. 2 is a vertical sectional view through the refrigerator illustrated in Fig. 1 showing the relation between a plurality of refrigerator compartments.

Fig. 3 is a horizontal section through my improved refrigerator substantially on the line 3—3, Fig. 1.

Fig. 4 is a horizontal section through the refrigerator substantially on the line 4—4, Fig. 1, and showing the door open, with one of the compartments exposed.

Fig. 5 is a detail perspective view of the compartment forming unit or frame in disassembled relation to its supporting shell or cabinet.

Fig. 6 is a detail perspective view, partly in horizontal section, of an end of a compartment wall showing an arrangement for forming a seal between the compartment walls and refrigerator.

Fig. 7 is horizontal section through a modified form of refrigerator embodying this invention and showing a particular arrangement of cabinet wall structure relative to a movable compartment forming frame therein.

Referring more in detail to the drawings:

1 designates a refrigerator embodying the features of the present invention which preferably consists of a cabinet adapted to be mounted in a corner of a room, the cabinet having a vertical rear wall 2 from the side edges of which walls 3 and 4 diverge, the walls 3 and 4 being connected at their forward edges with the rear edges of converging walls 5 and 6. The walls 5 and 6 terminate at the side edges of a front wall 7. As shown in Fig. 2, the cabinet is also provided with a bottom wall 8 mounted on suitable standards 9 and a top wall 10 connecting the edges of the front, side and rear walls of the cabinet.

11, Fig. 2, designates a transversely arranged support, preferably secured at its ends, as at 12, to the inner faces of the front and rear walls of the cabinet. The support 11 cooperates with the bottom wall of the cabinet in defining a lower compartment 13 that may be used for desirable purposes, such as storage, and a door 14 is provided to normally close an opening 15 in the cabinet front wall leading to the compartment 13.

Mounted on the support 11 is a plate or the like 16 and an insulating bed 17 of suitable material is mounted on the plate. The bed 17 preferably has a plan of approximately two-thirds of a circle, a chord, approximating the width of the cabinet front wall 7, defining the forwardly arranged edge of the bed. An arcuately shaped wall 18 projects upwardly from the bed 17, the wall being of a suitable material and thickness 19, Fig. 4, through a portion thereof and a relatively greater thickness 20 throughout the remainder thereof. The said wall portions are preferably distorted, as at 21 and 22, to provide spaces 23 and 24 for cooling or like devices or coils 25 and 26, the coils 26 preferably being greater in number or effectiveness than the coils 25, to the end that the temperature in one portion of the refrigerator may be reduced to a greater degree than other portions thereof, the greater wall thickness noted aiding in maintaining such difference in temperatures.

An inner, preferably porcelain covered metallic wall 27 bounds the inner surface of the wall 18 in surrounding relation to the cooling coils. The wall 27 preferably joins the outer cabinet walls after being offset, as at 28, Fig. 4, to cover a shoulder 29 of the wall 18 and being extended outwardly as at 30 and 31 to define an opening 32 leading to the compartment enclosed within the wall 21. A door 33, insulated as at 34, is preferably hinged, as at 35, to a wall of the cabinet in such a manner as to close the opening 32, the door being controlled by a latch 36 thereon and

a cooperative latch 37 on the cabinet proper. The wall 18 is of a height sufficient to extend above the door opening and is provided with a set-back 38, Fig. 2, extending horizontally to the bottom edge 39 of a frusto-conical upwardly extending projection 40 the hollow interior of which forms a compartment 41. The upper end of the compartment 41 is provided with a bolt 42 or the like the upper end of which is secured at the juncture of preferably crossed reinforcing bars 43 and 44 that may be braced as at 45 and form an interior framework for the refrigerator cabinet, as shown.

The walls 18 and 27 may also be arranged to provide projecting portions 46 and 47, Fig. 3, to define an ice-cube compartment 48 adjacent the coils 25, which compartment may be closed at its outer end by a door 49 hinged to the cabinet and having a suitable latch.

The support 11, plate 16, bed 17 and bottom portion of the wall 27 are provided with apertures for the passage of a tie-bolt 50, Fig. 2, which also passes through apertures in preferably circular bearing plates 51 and 52 that preferably have ball bearings 53 therebetween.

In Fig. 5 a compartment forming frame or the like 54 is illustrated which is arranged for enclosure within the cabinet 1 and wall 27, the frame preferably consisting of a base or bottom wall 55 having a centering pin 56 or the like engageable with the tie-bolt 50, Fig. 2, to rotatably mount the frame in the cabinet on the ball-bearing plates. The base 55 is of the general shape of the horizontal cross section of the interior of the wall 27, i. e., of generally circular shape and having a front face defined by a chord 57 that cuts off approximately one-third of the arc of the circle.

A vertically arranged partition wall 58, Figs. 3 and 4, projects upwardly from the base of the frame in such a manner as to cooperate with the cabinet wall 27 in forming compartments 59 and 60 in the refrigerator. The preferable arrangement for the wall 58 is that a portion 61 thereof is positioned substantially midway between the outer ends of the chord 57 relative to the periphery of the base 55, such portion extending inwardly toward the center of the base a distance, as at 62, short of such center and sufficiently to define a shelf area in the compartment 59. The wall 58 follows an arc of approximately one-third of a circle from the point 62 to the point 63, in concentric relation to the center of the base 55, where it branches, one portion 64 of the wall projecting to one end of the chord 57 and the other portion 65 projecting on a tangent of the circle to the other end of the chord, as shown in Fig. 3. The wall 58 and its branches are preferably of insulating material covered by enameled or similarly coated metal 66 that is suitable for supporting brackets 67 or the like and shelves 68 on one side thereof and brackets 69 on the other side thereof in the respective compartments. The end edges of partition 58, as shown in Fig. 6, are preferably concave in cross-section, and are provided with a sealing strip S provided with a felt or like filler F secured to said edges by suitable fastening devices and arranged for wiping contact with the wall 27 to create an effective seal and obviate heat transfer between the compartments 59 and 60.

Mounted in the space 10, Figs. 3 and 4, between the wall 27 and frame 54 adjacent the shoulder 29 near the cabinet door opening is a pulley 71, Fig. 5, over which runs a tiller rope 72, one end

5 of which is provided with a weight 73 depending into the space 10 and the other end of which is run under a pulley 74 that is suitably mounted in the cabinet. The rope is secured at its extremity 75 to a substantially circular channel 76 that is secured in concentric relation to the bottom face of the base 55 of the compartment forming frame 54.

10 It is believed apparent that the channel and rope may be arranged to normally present the branches of the wall toward the door opening of the cabinet and that the normal action of the weight is to swing the compartment 59 toward the door opening.

15 Swinging movement of the frame is preferably controlled by a latch 77, Figs. 3 and 4, that is engageable with the edges of the partition, as shown for example in Fig. 3, to hold the frame in desired position, the latch being supported on 20 a rod 78 extending through the cabinet front wall to a point adjacent the door latch 37. A handle 79 may be provided to latch or unlatch the partition as desired.

25 Arranged in the fork between the branches 63 and 65 of the partition 58 is a recess 80 for reciprocably receiving weights 81 mounted on a tiller rope 82 that extends over a pulley 83 on the top wall 84 of the frame 54 and passes over a hollow frusto-conically shaped portion 85 of 30 the top wall, that fits within the projection 49 of the cabinet, to and over a pulley 86 that is swivelly mounted on the bolt 42. From the pulley 42, the rope 82 depends through the top portion 85 of the frame into the interior of the compartment 60 of the refrigerator where the lower end of the rope may be provided with a suitable hook 87 for supporting articles of food, such as a quarter of beef. It will be noted that the portion 85 may substantially cover the hook and that the effective space to be refrigerated is reduced to a minimum.

35 Assuming a refrigerator to be constructed as described, its operation is as follows:

40 The refrigerator door 33 is opened and the latch 77 operated to allow the weight 73 to move the frame 54 to present the compartment 59 to the door opening, as shown in Fig. 4. Articles to be refrigerated may be applied to the shelves 68, whereupon the frame may be returned to the 45 position shown in Fig. 3 and beyond, against the weight 63, to present the compartment 60 to the door opening, where it may be held in position by the latch 77. Larger articles of food such as meats, fowl, fish and the like due to the additional space provided by the curvature of the partition 58 and cone-shaped hollow projection 85 may then be suitably applied to the hooks and brackets in the compartment 60, the weights 81 suspending the articles on the hook 87 and facilitating their handling. The frame then returns to the position shown in Fig. 3 under action of the weight 73 where it may be held by operating the latch 77, so that the cabinet door may be closed.

50 It will be noted that when one compartment is presented to the cabinet door opening, the other compartment remains enclosed, thus avoiding unnecessary heat transfer that is normally encountered in conventional refrigerators. It 55 will also be noted that one of the compartments may be cooled to a temperature lower than the other and a temperature difference effectively maintained.

50 In Fig. 7, a modified form of refrigerator embodying this invention is shown, wherein the

compartment forming frame 90 is preferably substantially similar to the frame 54 previously described, as is the door 91 of the cabinet 92. In the present instance, the walls 93, 94, 95, 96 and 97 take the place of the insulating walls 17 in the preferred form of invention and consist of suitable insulation enclosed in preferably enameled metal sheathing outer walls.

Cooling devices 98 and 99 are mounted in the spaces 100 and 101 between the cabinet walls and compartment forming frame, the cooling device 99 being adapted to cool the compartment 102 to a lower temperature than the compartment 103 is cooled by the cooling device 98, whereby meats and other edibles requiring more severe refrigeration for preservation than vegetables, for example, may be properly kept over long periods of time.

The operation of the modified form of invention is substantially the same as the preferred form of invention.

It is apparent, therefore, that the present invention provides a convenient, relatively economical and highly efficient refrigerator for the purposes above noted.

What I claim and desire to secure by Letters Patent is:

1. A refrigerator of the character described including a refrigerator cabinet having a door opening, a frame rotatably mounted in the cabinet adapted to carry articles to be refrigerated, means dividing said frame into compartments, and means in the compartments respectively for cooling said compartments to different temperatures respectively.

2. A refrigerator of the character described including a cabinet having a door opening, a frame rotatably mounted in the cabinet adapted to carry articles to be refrigerated, said frame being rotatable in opposite directions, means dividing said frame into vertically arranged laterally spaced compartments, one of said compartments extending substantially from the top to the bottom of said cabinet and means for presenting said compartments respectively to said door opening.

3. A refrigerator of the character described including a cabinet having a door opening, a door for said opening, a frame rotatably mounted in the cabinet adapted to carry articles to be refrigerated, means dividing said frame into compartments, means operable in opposite directions for presenting said compartments respectively to said door opening, and means for moving said presenting means in one direction in response to opening of said door.

4. A refrigerator of the character described including a cabinet having a door opening, a frame rotatably mounted in said cabinet, a partition on said frame dividing said cabinet into compartments, said partition being adapted to close said door opening, means for moving said frame to present one of said compartment at said door opening and allowing presentation of another compartment at said opening upon rotating said frame, and means for cooling said compartments.

5. A refrigerator of the character described including a cabinet having a door opening, a frame rotatably mounted in said cabinet, a partition on said frame dividing said cabinet into

compartments, said partition being adapted to close said door opening, means for moving said frame to present one of said compartment at said door opening and allowing presentation of another compartment at said opening upon rotating said frame, and means for cooling said compartments to different degrees of temperature.

6. A refrigerator of the character described including a cabinet having a door opening, a frame rotatably mounted in said cabinet, a partition on said frame dividing said cabinet into compartments, said partition being adapted to close said door opening, means for moving said frame to present one of said compartment at said door opening and allowing presentation of another compartment at said opening upon rotating said frame, means for cooling said compartments to different degrees of temperature, and sealing means on edges of said partition having wiping engagement with portions of said cabinet to reduce heat transfer between compartments.

7. A refrigerator of the character described including a cabinet, means dividing said cabinet into compartments, means for cooling said cabinet, and a balancing device arranged in said cabinet for facilitating handling of articles within one of the compartments of said cabinet.

8. A refrigerator of the character described including a cabinet, means for cooling said cabinet, means in said cabinet depending from an elevated portion thereof for supporting articles to be cooled, and means in the cabinet for substantially enclosing a portion of said supporting means to reduce the effective space to be refrigerated.

9. A refrigerator of the character described including a cabinet, means for cooling said cabinet, means in said cabinet for supporting articles to be cooled, said supporting means including a partition having a portion extending inwardly relative to said cabinet and a portion following an arc of a circle substantially concentric with the axis of said supporting means to increase the space on one side of said supporting means relative to the other side thereof, and a portion extending outwardly relative to said arc for defining a plurality of compartments relative to said supporting means.

10. A refrigerator of the character described including a cabinet, means for cooling said cabinet, means dividing the cabinet into refrigerated compartments, a balancing device in the cabinet for facilitating handling of articles within a compartment of said cabinet, and a recess in said cabinet for receiving a portion of the balancing device to reduce the amount of ineffective refrigerated space in said refrigerator.

11. A refrigerator of the character described including an insulated cabinet, means for cooling said cabinet, a frame mounted in said cabinet, said cabinet and frame being arranged relative to each other to provide a space therebetween, and an article supporting device positioned interiorly relative to said frame and supported exteriorly relative to the frame within the cabinet, said device having means connected therewith and arranged in said space for balancing an article supported by said device.
